UNITED STATES PATENT OFFICE

147,404

DESIGN FOR A WATER FAUCET

Emil H. Fitter, Woodside, N. Y., assignor to Fitter Valve Division of the Tumpane Company, Long Island City, N. Y., a partnership composed of John J. Tumpane, Smithtown Branch, Long Island, N. Y., James P. Tumpane, Jr., East Elmhurst, Long Island, N. Y., and Emil H. Fitter, Woodside, Long Island, N. Y.

Application May 3, 1946, Serial No. 129,251

Term of patent 3½ years

(CL. D4—3)

To all whom it may concern:

Be it known that I, Emil H. Fitter, a citizen of the United States, residing at 50-27 63rd Street, Woodside, Long Island, in the county of Queens and State of New York, have invented a new, original, and ornamental Design for Water Faucets, of which the following is a specification, reference being had to the accompanying drawing, forming part thereof.

The figure is a perspective view of a water faucet, showing my new design.

I claim:

The ornamental design for a water faucet, as shown.

EMIL H. FITTER.
